UNITED STATES PATENT OFFICE.

FREDERICK HENRY HAVEKOTTE, OF CINCINNATI, OHIO, ASSIGNOR TO HIMSELF AND FRANK KYRLACH, OF CINCINNATI, OHIO.

FAUCET.

SPECIFICATION forming part of Letters Patent No. 730,646, dated June 9, 1903.

Application filed October 14, 1902. Serial No. 127,265. (No model.)

To all whom it may concern:

Be it known that I, FREDERICK HENRY HAVEKOTTE, a citizen of the United States, and a resident of Cincinnati, in the county of Hamilton and State of Ohio, have invented a new and Improved Faucet, of which the following is a full, clear, and exact description.

This invention relates to an improvement in gate-faucets of that class in which the gate is arranged to move transversely of the tube over the end thereof to open or close the tube, these devices being used in connection with heavy or semisolid liquids. In faucets of this sort difficulty has been experienced in preventing the accidental opening of the gate; and my invention seeks to provide a means for securing the gate not only against accidental opening, but against fraudulent opening. This end I attain by providing a lock device for the gate which with the aid of a suitable key may be thrown into action, thus preventing the gate from being opened, and when it is desired to open the gate a slight application of the key releases the lock.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is a side view of the invention. Fig. 2 is a plan view thereof. Fig. 3 is a longitudinal section thereof, and Fig. 4 is a view of the key.

a indicates the tube, which is curved slightly downward at its discharge end and which has said end shaped in an arc, as indicated at *a'*.

b indicates the gate, which is fitted to slide over this arc-shaped end, and *c*, Fig. 2, indicates the arm which is mounted to swing on the tube *a* and carries the gate. This arm is here shown to comprise a fork *c'*, straddling the tube and pivoted thereto, a finger-piece

*c*², projecting upward and forward from the crotch of the fork *c'*, and a casing *c*³, projecting forwardly beneath the finger-piece *c*². The arm *c* is preferably formed in two longitudinal sections fastened together by screws *c*⁴. (See Fig. 1.)

*c*⁵ indicates a lug on the fork *c'*, this lug

working between stops *a*² on the tube *a* to limit the throw of the arm *c*.

The gate *b* is fitted loosely between the arms of the fork *c'* and has formed on its outer side a stud *b'*, in the end of which is produced a conical recess, this recess receiving the conical end of a screw *d*, the threaded portion *d*¹ whereof works in the correspondingly-threaded portion *c*⁶ of the casing *c*³. The outer end *d*² of the screw is of a square or other angular form, so as to fit the key *f*. (Shown in Fig. 4.) The outer end of the case *c*³ is formed with a cavity *c*⁷, which facilitates the introduction of the key and yet prevents the application of a wrench to the square end *d*² of the screw *d*.

g indicates a spring which is contained in the case *c*³ and which exerts a steady pressure on the gate *b*, holding it snugly against the tube *a* independently of any action of the screw *d*.

In the operation of the device when it is desired to lock the gate the faucet should be closed and then the screw *d* tightened, so as to press forcibly against the gate and hold it in place. This action of the screw may be carried so far as to prevent the faucet from being opened even by the use of a hammer or other heavy instrument. To unlock the faucet, it is only necessary to relax the pressure of the screw, whereupon the gate will be held against the tube only by the action of the spring *g*. Should the spring break, the screw will nevertheless hold the valve closed.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. In a faucet, the combination of a tube, stops on the tube, a gate, a swinging arm having a fork pivoted to the tube, lugs on said fork for engaging said stops to limit the throw of the fork, said arm being provided at its upper outer end with a handle and having a cavity with a reduced threaded portion near the outer end thereof, a screw threaded

in said reduced portion and provided with a square outer end and a conical inner end, said gate having on its rear side an outwardly-extending projection in alignment with said screw and of equal diameter therewith, said projection being provided on its outer end with a conical recess to be engaged by the conical end of the screw, and a compression-spring lying in the inner end of said cavity in the swinging arm, said spring bearing continuously against the gate and engaging the periphery of the cavity with its outer diameter and at its inner end surrounding the projection on the gate and thereby serving to hold the gate in operative connection with the swinging arm independent of said screw.

2. In a faucet, the combination of a tube, a swinging arm having a fork pivoted to the tube, a gate interposed between the end of

the tube and the swinging arm and having on its rear side an outwardly-extending projection with a conical recess in its end, said swinging arm being provided with a handle and having a bore or cavity opposite the end of the tube, and a screw having a conical inner end extending into said cavity, with its conical end in engagement with the conical recess in the projection of the gate, whereby said gate is held against the end of the tube and is moved back and forth with the swinging arm, as set forth.

In testimony whereof I have signed my name to this specification in the presence of two subscribing witnesses.

FREDERICK HENRY HAVEKOTTE.
